(57) **CLAIM**

The ornamental design for swing-out mount for flat panel displays, as shown and described.

DESCRIPTION

FIG. 1 is a top isometric view of a swing-out mount for flat panel displays showing our design in a vertical configuration.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof; and,

FIG. 7 is a bottom plan view thereof.
